UNITED STATES PATENT OFFICE.

AUGUST H. HESTERHAGEN, OF JERSEY CITY, NEW JERSEY.

ELECTRIC-WIRE COUPLING.

964,969.

Specification of Letters Patent. Patented July 19, 1910.

Application filed April 14, 1910. Serial No. 555,421.

To all whom it may concern:

Be it known that I, AUGUST H. HESTERHAGEN, a citizen of the United States, residing in Jersey City, Hudson county, and State 5 of New Jersey, have invented certain new and useful Improvements in Electric-Wire Couplings, of which the following is a specification.

The object of my invention is to provide 10 a simple, cheap, compact and effectively insulated coupling for electric wires,—one that may be used in any emergency and under all conditions of use with perfect safety, at the same time dispensing with soldered or spliced 15 joints or other expensive and complicated forms and methods of connection.

It is well known that the conditions and 20 restrictions imposed by official authority are exacting and require absolute and perfect insulation of all metallic connections and parts; also that soldered and spliced joints are expensive by reason of the skilled labor involved, and are not even then always reliable. I obviate these difficulties and meet 25 all requirements by my invention which affords a positive electrical connection so simple and compact that it may be quickly and conveniently applied and used even in situations and positions that would be otherwise 30 inaccessible.

The invention consists in the specific construction and arrangement of parts described and claimed, distinguishing features being the embedding of the metallic coupling 35 in a base section of insulating material, and a cap section of insulating material secured to the base by a binding screw and nut, the latter being embedded in one section and the screw passing through the other 40 section and being isolated from the metallic coupling by the material of both sections.

Incidentally the invention includes certain minor details of construction hereinafter described.

In the accompanying drawings, Figure 1, 45 is an elevation of my improved single connection coupling; Fig. 2, a view of the inner side of the base section; Fig. 3, a view of the inner side of the cap section; Fig. 4, a trans- 50 verse section upon plane of line 4—4—Fig. 1; Fig. 5, a transverse section upon plane of line 5—5—Fig. 1; Fig. 6, a transverse section upon plane of line 6—6—Fig. 1; Fig. 7, a transverse section upon plane of line 7—7—Fig. 1; Fig. 8, a section upon 55 plane of the line 8—8—Fig. 1; Fig. 9 is an

elevation of a double connection coupling made in accordance with my invention; Fig. 10 is an elevation of the inner side of the base section; Fig. 11, a view of the inner side 60 of the cap section; Fig. 12 is a transverse section upon plane of line 12—12—Fig. 9.

The metallic coupling plate m , is countersunk in the inner side of the base section b , and is secured in position by a shouldered 65 rear projection m' , embedded in the base section b ,—the latter being made of porcelain or other suitable non-conducting material. This shouldered back projection or anchor m' , may be conveniently formed of a 70 screw engaging a thread tapped for its reception in the coupling plate m ,—the head of the screw embedded in the base b , serving to hold the coupling plate rigidly in position, although this construction is not essential, since any suitable shouldered back projection of the coupling plate rigid therewith and embedded in the base section b , will serve to anchor 75 said coupling plate firmly in position on the 80 base section. The anchor m' , being entirely inclosed and sealed within the base section b , is obviously isolated and protected against contact with extraneous objects.

The metallic coupling plate m , is tapped 85 near each extremity with a screw hole m^2 , to receive the threaded shanks of the binding screws a , a , and concentric with these screw holes m^2 , are formed upturned flanges m^3 , which confine the loops w , w , of the ends 90 of the conducting wires w' , w' . The ends of the base section b , are formed with semi-circular grooves b' , for the accommodation of the insulated wire, and the ends of the cap section c , are likewise formed with corresponding grooves c' , c' , for the same purpose.

The cap section c , is made of non-conducting material and its inner face is recessed sufficiently to accommodate the heads of the 100 binding screws a , a , said cap section c , is secured to the base section b , by a screw s , and nut n , the latter being embedded in either section as may be desired or found most expedient. In the drawings the nut 105 is shown as embedded in the cap section c , and the base section b , is formed with a screw hole b^2 , extending through an insulating sleeve b^3 , projecting through a hole in the coupling plate m , as shown in Figs. 4, 110 8 and 12. This annular flange or insulating sleeve b^3 , effectually protects the screw s ,

from contact with the metallic coupling plate and prevents short circuiting. The screw hole b^2 , is also formed with a shoulder b^4 , for contact with the head of the screw 5 and this shoulder b^4 , is situated within the external surface of the section to insure the countersinking of the head of the screw sufficiently to protect the head against contact with extraneous objects, except such as 10 may be inserted in the hole. As a further precaution the outer end of the screw hole may be filled with wax or other sealing material if desired, although this is not essential since the isolation of the screw is 15 complete in so far as the metallic coupling plate is concerned.

To insure the proper alinement of the parts and prevent lateral movement of the sections upon the screw s , the base and cap 20 sections are formed on their inner sides with interlocking male and female parts 1 and 2, and these may obviously be formed alternately on either of the said parts. Thus in the drawings the male parts 1, are shown as 25 formed on the base section b , and the corresponding female parts 2 on the cap section c , but the arrangement may be reversed with like result,—the essential feature in this respect being the formation of interlocking 30 parts on the opposed contact surfaces of the sections that will effectually prevent lateral play or movement when the two sections are screwed together.

In the modification shown in the last four 35 figures of the drawings the structure is the same except that the insulating sleeve or flange b^3 , projects through side recesses m^4 , m^4 , in the metallic coupling plates m , m , and the base is also formed with a longitudinal 40 rib b^5 , interposed in position between said coupling plates. The duplex form of coupling shown in the last four figures is designed for special uses in which a plurality of connections are essential. Otherwise, 45 as, before stated, it is a mere duplication of the parts shown in the other figures of the drawings.

I am enabled to make my coupling so 50 small and compact that it may be conveniently used even in the relatively narrow contracted metallic moldings now prescribed as conductors for electric wires, as well as in outlet boxes, panel boxes and conduits generally. It is also especially adapted for 55 use in canopies and other contracted places in which the use of soldered or spliced joints would be impossible or dangerous. Furthermore in addition to its simplicity and cheapness it affords an absolutely safe, 60 positive means of connection. Another advantage of my construction of coupling is

that it is always accessible for inspection or substitution of wires and is a permanent device not destroyed by disconnection.

What I claim as my invention and desire 65 to secure by Letters Patent is,

1. An electric wire coupling comprising a base plate of non-conducting material, a metallic coupling plate formed on its back side with a shouldered anchor which is embedded in the base section, and also formed with screw holes for binding screws, said binding screws, a cap of non-conducting material fitting over the base, securing screw passing through one section and engaging 75 with a nut embedded in the other section, and said nut, for the purpose described.

2. An electric wire coupling comprising a base plate of non-conducting material, a metallic coupling plate countersunk in the 80 inner side thereof and formed on its back side with a shouldered anchor which is embedded in the base section, and also formed with screw holes for binding screws, said binding screws, a cap of non-conducting material fitting over the base section, a securing screw passing through one section and engaging 85 with a nut embedded in the other section, said nut, for the purpose described.

3. An electric wire coupling comprising a base plate of non-conducting material, a metallic coupling plate formed on its back side with a shouldered anchor which is embedded in the base section, and also formed with screw holes for binding screws, said binding screws, a cap of non-conducting material fitting over the base section, a securing screw passing through one section and engaging 95 with a nut embedded in the other section, said nut, the contacting surfaces of 100 the base and cap sections being formed with interlocking parts, for the purpose and substantially in the manner described.

4. An electric wire coupling comprising a base plate of non-conducting material, a 105 metallic coupling plate formed on its back side with a shouldered anchor which is embedded in the base section, and also formed with screw holes for binding screws, said binding screws, a cap of non-conducting material fitting over the base section, a securing screw passing through one section and engaging 110 with a nut embedded in the other section, and said nut, and an annular flange of the non-conducting material in one section interposed between the securing screw and the metallic coupling plate, for the purpose described.

AUGUST H. HESTERHAGEN.
